United States Patent Office

Des. 176,005
Patented Nov. 8, 1955

176,005

WRENCH

Philip Cariello, Brooklyn, N. Y.

Application January 19, 1955, Serial No. 34,072

Term of patent 14 years

(Cl. D54—16)

The single figure in the drawing is a perspective view of a wrench embodying my new design.

I claim:

The ornamental design for a wrench, substantially as shown.
